(57) **CLAIM**

The ornamental design for a tire changer operator control console, as shown and described.

DESCRIPTION

FIG. 1 is a top perspective view of a tire changer operator control console;

FIG. 2 is a front view of the tire changer operator control console;

FIG. 3 is a top view of the tire changer operator control console.

FIG. 4 is a bottom view of the tire changer operator control console;

FIG. 5 is left side view of the tire changer operator control console;

FIG. 6 is right side view of the tire changer operator control console; and,

FIG. 7 is a rear view of the tire changer operator control console.

The broken lines shown within the drawings illustrate features of the tire changer operator console that form no part of the claimed design.

1 Claim, 7 Drawing Sheets
